Design No 341.

W C Davis
Design for Stoves
Patented January 1st, 1857.

Fig. 1.

Fig. 2.

Dec. 341

William C. Davis of Cincinnati, Ohio.

Letters Patent No. 341 Dated Jan 11, 1851.

The Schedule referred to in these Letters Patent and making part of the same.

To all whom it may concern:

Be it known that I, Wm C.

Davis, of Cincinnati, in the County of Hamilton and State of Ohio, have invented, or produced a new Ornamental Design for Stoves, of which the accompanying drawings are a correct representation.

Fig. 1 being a view of the plate in front of the fire chamber &

Fig. 2 is a view of the side plate; both plates being represented with their appropriate doors, one of the fire doors being omitted in the drawing, the two being counterpart.

The moulding (a) around the various doors and panels, is represented in outline, by the dark lines at (a).

On either side of the fire doors is a panel (b) whose centre is decorated with a rosette (c). Each fire door has an oval panel (d); the corners between the panel and the quadrangular border are ornamented as shown at (e). The oven doors (f, g) have each a panel (h) of an oblong form, rounded at the ends, each of which contains at its centre, a rosette (i) and the intervals between the panels & the border are ornamented as at (j).

What I claim herein as new, and for which I desire Letters Patent, is,

The ornamental design for a Stove, substantially as represented in the accompanying drawings.

In Testimony whereof, I have hereunto set my hand before two subscribing witnesses.
